Inventor
Thomas Rendle.

UNITED STATES PATENT OFFICE.

THOMAS RENDLE, OF OTTAWA, ILLINOIS.

SHOE-REPAIRING STAND.

Application filed June 28, 1926. Serial No 118,988.

My invention relates to shoe repairing stands, for hand work and is an improvement on my Patent No. 1,556,350, dated October 6, 1925, and the objects of the invention consist in a special last mount, a standard, and a base spindle in one part; and a base in one part, to co-operate therewith.

I attain these objects by the mechanism illustrated in the accompanying drawing, in which—

Figure one (1) is a detailed view of the stand;

Figure two (2) is a plan view of the base;

Figure three (3) is a side view with reference to the cleat mount;

Figure four (4) is a perspective view of the heel part;

Figure five (5) is a detailed view of the special last mount standard and base spindle and

Figure six (6) is a plan view of the under side of the base.

The device consists of a circular standard one (1) having a tapered circular last mount two (2) and a rigidly fixed cleat three (3) at the rear having a concave groove at each side and a tapered slot therebetween, a heel part having a projecting breast in lieu of a concave breast, and two tapered arms being convex at the inner sides, to co-operate with the heel cleat in Figure three (3), a special tapered circular last mount two (2) rigidly fixed at one side of the standard, and a special tapered circular last mount two (2) rigidly fixed at the opposite side divided by a tapered slot, in lieu of the heel cleat, at one end, in Figure five (5), and a tapered circular base spindle at the opposite end provided with four angular grooves and a transverse perforation four (4), a base having an open tapered circular socket, provided with a set of four angular ridges and a transverse perforation five (5), and a channel passing through the diameter of the socket six (6) in the under side of the base between two perforations, and a pin, to co-operate with the

said perforations in the spindle and the base to fasten the base and the standard, a whole last seven (7) provided with a tapered circular socket and a concave groove in front, 50 and a shallow circular socket having an aperture at the rear, to co-operate with the circular mounts, a two sole last provided with two fore parts eight (8), having two tapered concave cleat mounts, rigidly fixed in opposite directions, positioned between the circular mounts, the heel part nine (9), to co-operate with the heel cleat and the cleats of the two sole last, the shoe holder comprising a gripping device encircling the standard and a 55 loop fastened to the arm to connect with the shoe, and a lag screw to fasten the base to a wood basis.

The method of operation is as follows:

The base spindle is loosely inserted in 65 the base socket and locked at right angles by the ridges, and securely fastened in each position by inserting a pin through the perforations in the base and base spindle.

I claim:

The combination in a shoe repairing stand, of a standard provided with a tapered circular last mount rigidly fixed at one side, and a special tapered circular last mount rigidly fixed at the opposite side, divided by a tapered slot, in lieu of the heel cleat, at one end, and a tapered circular base spindle at the opposite end, to co-operate with the socket of a whole last, and a two sole last mount positioned between the circular mounts, the base 75 spindle being provided with four angular grooves and a transverse perforation, a base provided with an open tapered circular socket having a set of four angular ridges and a transverse perforation, a channel passing 80 through the diameter of the socket and the base in the under side between two perforations, whereby the spindle and base may be locked from rotation and a pin passing through the perforations in the spindle and 85 the base to fasten the base and the standard. 90

THOMAS RENDLE.
